UNITED STATES PATENT OFFICE.

DAVID H. WILSON, OF CHICAGO, ILLINOIS.

SWITCHBOARD SYSTEM.

SPECIFICATION forming part of Letters Patent No. 514,980, dated February 20, 1894.

Application filed September 8, 1893. Serial No. 485,102. (No model.)

To all whom it may concern:

Be it known that I, DAVID H. WILSON, a citizen of the United States, residing at Chicago, county of Cook, and State of Illinois, have invented a new and useful Improvement in Switchboards, of which the following is a specification.

My invention relates to switchboards for electric fence stations and has for its object the production of a switch board having certain novel features which are set forth in the following description.

By the term "electric fence" I mean a fence made of wires or strands of some conducting material connected with a battery or generator in such a manner that when an animal standing on the ground comes in contact with such conducting wires a circuit will be completed through the body of the animal, causing said animal to receive a shock.

Referring to the accompanying drawings: Figure 1 is a front view of the switch board when in position. Fig. 2 is a diagram of the circuits of the switch board as seen from behind.

Like letters refer to like parts throughout. A is the switch board proper to which are secured the telephone transmitter A', the telephone receiver A², the bell A³, the switches B', B, B², B³ connected to the outgoing wires of the fence which in this case are four in number, and the switches B⁴, B⁵, B⁶, B⁷ connected to the incoming wires of the fence.

B⁸ is a switch by which the system is grounded.

Referring to Fig. 2, C is a generator which is connected by the wires C', C² to the binding posts D, D'.

C³ is a conductor leading from the binding post D' to the switches B⁴, B⁵, B⁶, B⁷, and B⁸.

C⁴ is a conductor leading from the binding post D through the coil of the electro-magnet C⁵ to the switches B, B', B², B³.

C⁶ is the armature of the electro-magnet C⁵. C⁷ is a contact point against which the armature C⁶ rests when said armature is attracted by the magnet C⁵.

C⁸ is a battery which works the bell A³.

E is the telephone battery, the terminals of which are connected to the binding posts E', E².

E³ is a conductor leading from the binding post E' to the transmitter A'.

E⁴ is the primary coil of an induction coil having one end connected to the transmitter A' and the other end connected to the contact plate E⁵.

E⁶ is a wire leading from the strip E⁷ back to the battery E.

E⁸ is the secondary coil of the induction coil having one end connected to the contact plate E⁹ and the other end connected to the binding post E¹⁰.

E¹¹ is a conductor leading from the strip E¹² to the ground.

E¹³ is a conductor connecting the binding port E¹⁴ with the binding post D³.

E¹⁵ is a telephone receiver.

E¹⁶ is a lever upon which the telephone receiver is hung when not in use.

E¹⁷ is a spring which tends to move the lever E¹⁶ away from the contact point E¹⁸.

The contact plate of the switch B is connected by the wire F to the frame F' of a telegraphic instrument which is represented diagrammatically with its several parts detached so as to allow the different circuits to be easily traced. The frame F' is provided with the slots F², F³ in which work the pins F⁴, F⁵. By this means the frame F' can be moved in or out of contact with the binding posts F⁷, F⁸.

F⁹ is the key, F¹⁰ the electro-magnets and F¹¹ the armature of the instrument.

F¹² is a battery one pole of which is connected to the electro-magnet F¹⁰ and the other pole grounded at F¹³.

F¹⁴ is a contact point which is connected by the wire F¹⁵ to the binding post F⁶.

F¹⁶ is a strip by which the binding posts F⁷ and F⁸ are connected.

G is a wire connecting the wire F¹⁵ with the binding post D².

K', K², K³, &c., are the contact plates of the different switches. The contact plates K² and K³ of the switches B² and B³ are connected to the binding posts D⁴ and D⁵. The contact plates K⁴, K⁵, K⁶, and K⁷ of the switches B⁴, B⁵, B⁶ and B⁷ are connected to the binding posts D⁹, D⁸, D⁷, D⁶. Switch B⁸ is connected to binding post D¹⁰ which is grounded by the plate H.

The outgoing wires of the fence are connected to the binding posts D², D³, D⁴, D⁵ and the incoming wires to the binding posts D⁶, D⁷, D⁸, D⁹. The first or top wire of the fence 5 is connected to the binding posts D² and D⁶, the second wire to the binding posts D³ and D⁷, &c.

The use and operation of my invention are as follows: When the instruments are in the 10 position indicated in Fig. 2, the circuit through the generator C is open. If an animal standing on the ground touches any of the wires of the fence the circuit will be completed through its body and it will receive a shock. When 15 the circuit is completed, the magnet C⁵ attracts the armature C⁶ and brings it in contact with the contact point C⁷. This completes the circuit through the bell A⁸ and sounds the alarm. Suppose the animal touches the top 20 wire of the fence the circuit will be traced as follows: from generator C to binding post D, thence to switch B, thence along wire F to the base F' of the telegraph instrument, thence along wire G to binding post D², thence 25 along the bottom wire of the fence to the animal, thence to ground, thence to plate H, thence back to the generator.

The circuit around the second wire of the fence is as follows: from generator C to binding 30 post D, thence to switch B', thence to conducting point E¹⁸, thence along lever E¹⁶, thence along spring E¹⁷ to binding post E¹⁴, thence by wire E¹³ to binding post D³, thence along the second wire of the fence to the animal, thence to ground, thence to plate H, thence to binding post D¹⁰, thence back to the 35 generator.

When it is desired to test the fence for 40 breaks, the operation is as follows. If it is desired to test the bottom wire, switch B⁸ is opened and switch B⁴ closed which completes the circuit through the generator and the fourth or bottom wire of the fence if that wire is all right. The circuit will be traced as follows: from generator C to binding post D, thence to switch B⁸, thence to binding post D⁵, thence along the bottom wire of the fence to binding post D⁹, thence to switch B⁴, thence by wire C³, back to the generator. If when 45 the switch B⁴ is closed the bottom wire of the fence is not broken, the electro-magnet C⁵ will attract its armature and complete the circuit through the bell A⁸ and cause said bell to ring. If the bell does not ring the bottom wire of the fence is broken. The third wire of the fence is tested in the same way by opening switch B⁴ and closing switch B⁵. If when in 55 this position the bell A⁸ rings the third wire is all right. The remaining wires of the fence are tested in the same manner, viz. by closing switches B⁶ and B⁷.

If a person anywhere along the fence desires to talk to a person at the station he grounds one wire of the hand telephone with 60 which he is provided and taps the fence with the other wire a certain number of times, the number being arranged between the two men.

This notifies the man in the station that he is wanted at the telephone. He then takes down the receiving telephone E¹⁵. The spring E¹⁷ 7c then moves the lever E¹⁶ until said lever moves out of contact with the contact point E¹⁸ and the strips E⁷ and E¹² come in contact with the contact plates E⁵ and E⁹. The current is then broken through the generator and completed through the transmitter A' and will be traced as follows: from battery E to binding post C', thence through wire E³ to transmitter A', thence through the primary coil E⁴, thence through contact plate E⁵, strip E⁷ 75 and wire E⁶ back to battery E. The circuit through the receiving telephone will be traced as follows: from secondary coil E⁸ to binding post E¹⁰, thence through the receiving telephone E¹⁵, thence to binding post E¹⁴, thence by wire F¹³ to binding post D³, thence along 80 the fence wire to the hand telephone of the man along the fence, thence to ground, thence to plate H, thence to binding post D¹⁰, thence along conductor E¹¹ to strip E¹², thence to contact plate E¹⁹ and thence back to the secondary coil E⁸. When the men cease talking the receiving telephone E¹⁵ is hung up again which breaks the circuit through the receiving and transmitting telephone. 95

If it is desired to use the telegraph instrument the man along the fence will give the prearranged signal. The man at the station then moves the base F' of the telegraph instrument in the direction of the arrow until 10c the binding post F⁷ and F⁸ are connected by the strip F¹⁶ and the connection between the base F' and the binding post F⁶ is broken. When in this position the generator C is out of circuit and the battery F¹² in circuit 105 with the instrument. The telegraph instrument is now ready for use. The circuit will be traced as follows: from battery F¹² through electro magnet F¹⁰, thence to binding post F⁸, thence along strip F¹⁶ to binding post F⁷, 110 thence to key F⁹, thence to contact point F¹¹ (when the key is pressed down) thence along wire G to binding post D², thence along fence wire to operator, thence to ground, thence to plate F¹³ and thence back to the battery F¹². 115 When the message has been completed the base F' of the telegraph instrument is moved to the position shown in Fig. 2 which breaks the circuit through the telegraph instrument and puts the generator C again in connection 120 with the top wire of the fence.

If the top wire of the fence should be broken and fall on the ground so as to ground that wire it can be thrown out of circuit by opening switch B, without affecting the remaining wires. Any of the wires can be thrown out of circuit should they become grounded in the same manner, viz., by opening one of the switches B, B', B², B³, corresponding to the grounded wire. 125

I claim—

A switch board for an electric fence having thereon binding posts and suitable connections for the fence wire and the generator, a

transmitting and receiving telephone, a lever upon which said receiving telephone is normally supported, conducting plates on the end of said lever, contact points adjacent thereto, a third contact point normally in contact with said lever, a telegraph instrument having a movable base, a strip attached to said base, contact points in proximity to said strip, a third contact point in proximity to said base, and suitable connections whereby

when the said telephone and telegraph instruments are connected to the fence wires, the connection of said wires with the generator is automatically broken, substantially as described.

DAVID H. WILSON.
